UNITED STATES PATENT OFFICE.

MAX ROTTER, OF MILWAUKEE, WISCONSIN, ASSIGNOR TO ALLIS-CHALMERS COMPANY, OF MILWAUKEE, WISCONSIN, A CORPORATION OF NEW JERSEY.

BLADE-FASTENING.

No. 899,622.

Specification of Letters Patent.

Patented Sept. 29, 1908.

Application filed October 10, 1906. Serial No. 338,223.

To all whom it may concern:

Be it known that I, MAX ROTTER, a citizen of the United States, residing at Milwaukee, in the county of Milwaukee and State of Wisconsin, have invented certain new and useful Improvements in Blade-Fastenings, of which the following is a specification.

This invention relates to fluid actuated mechanism, as turbines, or fluid forcing mechanism, as fans or pumps for liquids or gases, of the type in which are used a plurality of blades, usually arranged in groups, some of which are movable while others are stationary and serve as guide blades; and the purpose of this invention is to provide, in conjunction with blade fastening means, means which also serve as baffling members for the adjacent blades to prevent the passage of the operating fluid between said blades and an inclosing member or casing.

On the drawings which accompany this specification and form a part thereof and on which the same reference characters are used to indicate the same elements in each of the several views, Figure 1 represents an elevation of fragments of two adjacent blades, certain other parts being shown in section. Fig. 2 represents an elevation of fragments of two adjacent blades, other parts being shown in section, and showing a modification of the blade-securing means shown by Fig. 1.

On the drawings the reference letter R represents a blade holding member which is recessed at r, and said recess, as shown by the drawings, is provided with an undercut side at t, the opposite side of the recess being straight but provided with a bead or depression f.

Reference character B represents a blade provided with a root b which is seated in the recess of the member R and is adapted to be secured therein by the securing members c, d and e, as shown by Fig. 1, or by the securing members c and d, as shown by Fig. 2.

The securing members c may be a retaining strip of any preferred type or structure, while the securing member e is preferably composed of a metal which can be calked or driven between the member c and the adjacent side of the recess in the member R, and during such driving or calking will flow into the depression f thereby locking the parts securely together.

Reference character A represents a blade adjacent to the blade B which is provided on

its end with the shroud member s. The blades A and B, as shown by the drawings, are intended to represent either single blades or series of blades such as are used in steam turbines of the Parsons type, and, as shown by the drawings, it is immaterial whether the blades A be the movable blades and the blades B the immovable blades, or vice versa, the drawings being intended to show clearly the relative arrangement of the several parts and relation which one blade or set of blades bear to the next adjacent blade or set of blades.

In mechanism of the class to which this invention relates it is essential for obtaining the greatest efficiency that neither the operating fluid nor the fluid operated upon be permitted to pass by the working or movable blades without impinging upon their working faces.

This invention provides the blade holding member for one blade or one set of blades with means adapted to coöperate with the adjacent blade or set of blades to prevent the fluid passing by the end of such blade or set of blades and the adjacent blade-holding member.

In Fig. 2 the securing member c is shown as provided with the rib g, which is projected close to the shroud s which is secured to the free ends of the adjacent blades. This rib g is made of transverse thickness sufficient to stand the pressure exerted against it, while at the same time presenting a minimum surface to be contacted by the shroud s, should an actual contact take place.

With the construction just described, the projection g must be composed of the same material as the securing member c, said member on account of the strength required being constructed of a tough metal. With the construction as shown by Fig. 1, however, in which d is a separate member, shaped in cross section substantially as shown, placed between the members c and e and becomes a part of the blade-securing means, any suitable substance, whether it be metallic or not, may be used as the rib, as vulcanized rubber or asbestos, and such rib need not necessarily extend clear to the bottom of the recess, as shown by Fig. 1.

It will be apparent that by extending a part of the securing member d or the rib g towards the end of an adjacent blade or towards the ends of the adjacent blades and in

line therewith, a baffle member is provided which permits of considerable lateral displacement of the blades A as shown by the drawings, without enlarging the space existing between the shroud carried by said blade and the baffle member.

What I claim is,—

The combination with a blade - holding member R provided with a recess r, a blade 10 B seated in said recess, and the securing members c, d and e also seated in said recess,

the member d projecting from the blade-holding member R and adapted to serve as a baffle member for an adjacent blade A, said adjacent blade A, one of said blades being 15 movable with respect to the other.

In testimony whereof, I affix my signature in the presence of two witnesses.

MAX ROTTER.
